UNITED STATES PATENT OFFICE.

THOMAS P. MADDEN¹ OF ST. LOUIS, MISSOURI.

LOCOMOTIVE ASH-PAN.

1,107,682.

Specification of Letters Patent. Patented Aug. 18, 1914.

Application filed February 10, 1913. Serial No. 747,460.

To all whom it may concern:

Be it known that I, THOMAS P. MADDEN, a citizen of the United States, residing at St. Louis, Missouri, have invented a certain new and useful Improvement in Locomotive Ash-Pans, of which the following is a full, clear, and exact description, such as will enable others skilled in the art to which it appertains to make and use the same, reference being had to the accompanying drawings, forming part of this specification, in which—

Figure 1 is a side elevational view of a locomotive ash pan of my improved construction, and showing the lower portions of the front and rear legs of the fire box in section. Fig. 2 is a plan view of my improved ash pan. Fig. 3 is a rear elevational view of the ash pan. Fig. 4 is a sectional view taken approximately on the line 4—4 of Fig. 1. Fig. 5 is a transverse section taken approximately on the line 5—5 of Fig. 1. Fig. 6 is a detail sectional view taken at the upper end of the ash pan, showing a water supply pipe therein, and one of the nipples attached to said pipe.

My invention relates to new and useful improvements in locomotive ash pans, the principal objects of my invention being, to construct a comparatively simple, strong and durable ash pan which will effectively prevent the dropping of live coals onto the right-of-way, thereby meeting the requirements of the safety compliance laws; to construct an ash pan in such shape that it will resist all tendency to buckle or become distorted as a result of unequal expansion and contraction due to the variation of the heat of the ashes deposited in said ash pan, and further, to equip the ash pan with means in the form of a series of jet nozzles adapted to deliver water into the ash pan for the purpose of quenching the fire of all live coals within the ash pan and flushing all ashes from said pan whenever desired.

A further object of my invention is to provide air inlet openings in the sides of the pan, which openings admit the air necessary to support combustion of the fire on the grate above the ash pan.

To the above purposes my invention consists in certain novel features of construction and arrangement of parts hereinafter more fully described and claimed.

Referring by numerals to the accompanying drawings, 10 designates the depending

leg portions of the locomotive boiler, and fixed thereto in the usual manner is an ordinary mud ring 11. Fixed to and depending from this mud ring is the body 12 of my improved ash pan, the same being constructed of metal, and in the form of a chute which gradually becomes narrower and deeper from one end to the other. The forward and highest end of the body of the pan is formed on a gradual curve; for instance, on a curve having a thirty-two inch radius, and from this point the body of the pan gradually becomes deeper and narrower so that the extreme rear end has a comparatively small radius; for instance, a radius of approximately seventeen inches. The side portions of the body curve gradually upward and outward to meet the side portions of the mud ring 11, and formed in the upper portions of the sides of the body 12 immediately below this mud ring are openings 13 around which are arranged outwardly projecting housings 14. The upper ends of these housings 14 are opened, as designated by 15, in order to permit air to enter the upper portion of the ash pan, and which air passes from thence upward through the grate in the locomotive fire box.

By my improved construction the body of the pan is in the form of a tapered chute which declines from one end to the other, and for this reason all ashes and matter falling in the ash pan will, by gravity, tend to pass to the lower end of said pan. The upper portion of one end of the pan is closed by a fixed plate 16, and the lower portion of this end is normally closed by a hinged door 17. This door is operated by means of suitable mechanism such as toggle links 18 actuated by a lever 19 which extends to the locomotive cab, and thus said door can be locked in its closed position and opened from the cab whenever desired.

The wide end of the pan is closed by a plate 20, the upper portion of which is fixed to the corresponding portion of the mud ring 11. Positioned in the wide, shallow end of the pan is a tubular header 21 which preferably follows the curvature of the adjacent portion of the pan, and fitted into said header is a series of short nipples 22 which project downward toward the inclined curved bottom of the pan. The ends of these nipples 22 are cut off at an angle so that the jets of water issuing from said nipples will be deflected downward onto the

surface of the bottom of the pan. One end of this header is closed and connected to the opposite end is a pipe 23 which is tapped into one of the legs of the boiler, and located in this last mentioned pipe is a valve 24 which is controlled from the locomotive cab.

The door 17 at the lower end of my improved ash pan is normally closed and is locked in such position by the toggle links

10 18. All ashes from the fire box will drop into the ash pan, and by reason of the inclination of its bottom portion, said ashes will tend to gravitate toward the lower end of said pan. Thus the ashes are retained 15 within the ash pan and live coals are prevented from dropping onto the right-of-way.

When desired the valve 24 can be opened to permit water to pass into the header 21 20 and issue therefrom in jet form through the nipples 22, which jets pass downward over the bottom of the ash pan, flushing out the ashes therein and killing or quenching any live coals in said ashes. The door 17 is 25 opened by manipulating the lever 19 from the cab, and as the water continues to issue in jets from the header, the entire contents of the ash pan is flushed out through the open lower end.

30 My improved ash pan can be varied slightly in shape and construction so as to be utilized in connection with different styles of locomotives.

It will be noted that the body of the 35 improved ash pan is curved in cross section throughout its entire length, and by such construction I materially stiffen the pan against any tendencies to warp or become distorted and out of shape by reason of unequal expansion or contraction due to varying degrees of temperature within the pan.

The main body of the pan may be either formed of sheet metal or cast, and it may be formed in a single piece or made in sections.

45 It will be readily understood that minor changes in the size, form and construction of the various parts of my improved ash pan can be made and substituted for those herein shown and described without departing from the spirit of my invention, the scope of which is set forth in the appended claims.

I claim:

55 1. The combination with a locomotive fire box, of an ash pan arranged beneath said fire box, the main body portion of which ash pan is constructed from a single piece of material in the form of an elongated chute, which is curved in cross section, and the bottom of which pan is inclined lengthwise, there being air inlet openings formed in the upper edges of said ash pan, a transversely disposed water supply pipe at the 60 upper wide end of the pan, and a series of

jet nozzles projecting from said pipe downwardly onto the inclined bottom of the pan, the lower ends of which jet nozzles are cut off at an angle so that the water issuing from said jet nozzles is delivered directly downwardly at an angle onto the surface of the bottom of said pan.

2. The combination with a locomotive fire box, of an ash pan arranged beneath said fire box, the main body portion of which ash pan is constructed from a single piece of material in the form of a chute which gradually becomes narrower and deeper toward one end there being air inlet openings formed in the upper portions of the side walls of said ash pan, a fixed wall closing the upper portion of the narrow deep end of the pan, a door arranged beneath said fixed wall for normally closing the lower portion of the narrow deep end of the pan, and means for delivering water on the wide and shallow end of said pan.

3. The combination with a locomotive fire box, of an ash pan arranged beneath said fire box, the main body portion of which ash pan is constructed from a single piece of material in the form of a chute which gradually becomes narrower and deeper toward one end there being air inlet openings formed in the upper portions of the side walls of said ash pan, a fixed wall closing the upper portion of the narrow deep end of the pan, a door arranged beneath said fixed wall for normally closing the lower portion of the narrow deep end of the pan, a transversely disposed water supply pipe arranged in the wide shallow end of the pan, and a series of jet tubes projecting from said water supply pipe downwardly onto the bottom of said ash pan.

4. The combination with a locomotive fire box, of an ash pan arranged beneath said fire box, the main body portion of which pan comprises a single piece of material, the central portion of which is in the form of a chute, which gradually becomes narrower and deeper toward one end, the side walls between the central portion and the sides of the fire box being curved upwardly and outwardly, portions of the upper edges of said side walls being cut away to form air inlet openings and housings fixed to the sides of the pan around said openings.

5. The combination with a locomotive fire box, of an ash pan arranged beneath said fire box, the main body portion of which pan comprises a single piece of material, the central portion of which is in the form of a chute, which gradually becomes narrower and deeper toward one end, the side walls between the central portion and the sides of the fire box being curved upwardly and outwardly there being air inlet openings formed in the upper portions of said side walls, housings fixed to the sides of

the pan around said air inlet openings, a transversely disposed water supply pipe arranged at the wide shallow end of the ash pan, a series of jet tubes projecting from 5 said water supply pipe downwardly onto the curved inclined bottom of the pan, and a wall closing the narrow deep end of the pan, a portion of which wall is movable to permit the escape of ashes and water 10 from the pan.

6. As a new article of manufacture, a locomotive ash pan having a body in the form of a chute, which gradually becomes

narrower and deeper toward one end the upper edges of which chute are cut away at 15 predetermined points to provide air inlet openings and open topped housings applied to the outside of the chute around said air inlet openings.

In testimony whereof I hereunto affix my 20 signature in the presence of two witnesses, this 25th day of January, 1913.

THOMAS P. MADDEN.
